UNITED STATES PATENT OFFICE.

CHARLES BUTTERFIELD, OF NOTTINGHAM, ENGLAND.

PRINTING-MACHINE.

1,009,647.

Specification of Letters Patent. Patented Nov. 21, 1911.

Application filed March 23, 1909. Serial No. 485,226.

To all whom it may concern:

Be it known that I, CHARLES BUTTERFIELD, a subject of the King of Great Britain, and a resident of Nottingham, England, 5 have invented new and useful Improvements in Printing-Machines, of which the following is a specification.

This invention relates to improvements in platen printing presses fitted with a platen 10 which remains stationary during the operation of printing, the object of the present invention being the construction of a platen printing press which can be worked at a high speed and for which purpose the machine is 15 fitted with improved mechanism for feeding the sheets to the machine, improved gripper mechanism by which the sheets are taken from the feeding mechanism to the printing position and from the printing position to 20 the delivery mechanism, improved ink plate mechanism whereby the variation in the tension of the roller springs is reduced to a minimum and the rollers prevented from jumping when running at a high speed, improvements in mechanisms connected with 25 the mechanisms above referred to and improvements in the general construction and arrangement of the machine.

In the accompanying drawings:—Figure 30 1. is an elevation of the right hand side of the machine. Fig. 2. is a part sectional elevation of the machine with the right hand standard removed. Fig. 3. is a part left hand side elevation of the machine. Fig. 35 4. is a section on the line A. A. Fig. 3. Fig. 5. is an elevation showing the connection between the stop rod and the automatic and the hand "throw out" mechanisms. Fig. 6. is a transverse section through the 40 grippers looking toward the right hand standard. Fig. 7. is a sectional elevation of the feeding table and connected mechanism with the table in its feeding position. Fig. 8. is a sectional elevation of the feeding 45 table and connected mechanism with the table in its lowest position. Fig. 9. is an elevation of the feeder mechanism showing also the connection with the disconnecting mechanism. Fig. 10. is a plan of the mechanisms shown in Figs. 7, 8 and 9. Fig. 11 is a side elevation of the end of the impression rod, its supporting plate and parts directly associated therewith. Fig. 12 is a 50 sectional elevation of one set of grippers. Fig. 13 is a horizontal sectional view, viewed from above, of the rod carrying the gripper

locking fork, and the arms which prevent the turning of the same.

In the machine shown in the drawings the platen 1 forms part of a frame or stretcher 2 which is rigidly attached to the standards 3 and 4. The type bed 5 is adjustably attached to the type bed legs 6 which are fitted to oscillate on an axle 7 and at the back form bearings for a shaft 8 which has 60 axles 9 eccentric thereto. These axles are connected by links 10 to axles 11 and 12 on the wheels 13 and 14 which are mounted on a shaft 16 and driven from the driving shaft 18 through a pinion 17 which engages with the wheel 13. The shaft 8 is so arranged that the impression is normally in its "on" position and on one end of the shaft there is an impression arm 18 by which the shaft 8 is turned through the impression rod 19 to throw the impression "off" by hand or automatically as herein-after explained.

Fitted to oscillate on the shaft 8 are the ink roller arms 20 carrying the ink rollers 21 Fig. 1., and connected by a link 22 Fig. 3 to the standard 4 by which arrangement the arms 20 are actuated in the usual manner. The ink plate 23 Fig. 1 is fitted to rotate in a bracket 24 which is pivotally connected to the top of the type bed or to a bracket carried by the type bed legs 6, and the back end of the bracket 24 is connected by a link 25 to an arm 26 which is carried by the tie bar between the ink roller arms 20. The pawl 27, for intermittently rotating the ink plate 23, is carried by a lever 28 which is pivoted on the bracket 24 and is actuated as it comes into contact with the cam surface 29 on the bracket 26. By this arrangement the back end of the ink plate is lowered as the ink rollers 21 move toward the ink duct roller 30 and is raised as the ink rollers move in the opposite direction whereby a minimum variation in the tension 95 of the ink roller springs is obtained. When the impression is "on" one of the ink rollers comes into contact with the ink duct roller 30 when the ink rollers are at the end of their backward movement, but the ink rollers do not reach the ink duct roller when the impression is "off" owing to the fact that the shaft 8 is turned and the type bed does not move so far forward.

Rigidly connected to the platen stretcher 110 or bracket 2 there are the gripper bearing rings 31 and 32 and fitted to revolve on

these rings respectively there are the gripper carrying rings 33 and 34 which are rigidly connected together by the fixed grippers 35. The movable grippers 36 are carried by side levers 37 which are centered at 38 on the gripper rings 33 and 34, and normally the grippers are held closed by suitably arranged springs 38*. The gripper ring 33 is provided with gear teeth which 10 engage with a pinion carried by a shaft 39 and on the same shaft there is a second pinion which is engaged intermittently with a rack 40. This rack is pivotally connected at 41 to a slotted lever 42 which is fulcrumed at 43 and is actuated by a crank pin 44 on a disk 45 which is fixed upon a shaft 46 and driven by a claw finger 47 on a gear wheel 48 which is loosely mounted on the shaft 46 and is driven from the wheel 13, 20 through which arrangement the shaft 46 and the cams upon it are also driven, while the use of a slotted link 42 for driving the rack 40 gives a quick return motion to the rack. At the end of each forward movement of the rack it is raised out of gear with its pinion and at the end of each back stroke the rack is lowered into gear with its pinion by which arrangement an intermittent rotation is given to the grippers. To 30 enable this to be effected the rack is fitted to slide horizontally in a guide 49 which is slotted to slide vertically on a die 50 encircling the shaft 46 and is raised and lowered from a cam 51 on the shaft 46 through 35 a lever 52, rocking shaft 53 and lever 54. For locking the gripper rings in position after each movement and for making sure that the grippers have been moved to their printing and registering position the gripper ring 33 is provided with locking lugs 55 Figs. 1 and 2 and working in conjunction therewith there is a fork 56 carried by a bar 56* which is fitted to slide in brackets 57 on the standards 3 and prevented from turning 40 by arms 58, Figs. 1 and 13, which slide in contact with the face of the standard. The fork 56 is actuated from the cam 59 on the shaft 46 through a lever 60 and a buffer spring 61 which is introduced to insure that 45 50 the fork 56 is positively raised to its locking position. The end of the lever 61 lies between a pair of collars 160, 161, the former of which is fast and the latter loose upon the bar 56*; and the spring 61, which 55 surrounds the bar 56*, bears at one end against the loose collar 161 and at its other end against a collar 160 fast upon the bar. The spring is strong enough to support the weight of the fork 56 and the rod 56*, and 60 is somewhat compressed when the fork is lifted to its locking position. This arrangement insures an accurate operation of the locking fork even should the cam by which the movements are controlled become worn.

55 The frisket irons 62 for holding the sheet

on the platen are adjustably attached to a bar 63 which is carried by levers 64 from a rocking shaft 65, and rigidly connected to one end of the bar 63 there is a lever 66, the face of which slides in a guide 67 whereby the position of the frisket irons 62 is controlled as they are moved to and from the platen. For actuating the shaft 65 it is fitted with a lever 68 which is coupled by a link 69 to a lever 70 which is actuated by the cam 71 on the shaft 46, see Figs. 2 and 4.

The end 72 of the impression rod 19 slides upon a plate 73 which is pivoted on the standard 3, and normally this plate is so held by a wedge on the spring 74 that the end of the rod 72 is directed over the impression stop 75, but when the impression is thrown "off" the wedge is withdrawn from under the plate 73 and the weight of the rod tips the plate and the end of the rod 80 strikes against the stop 75 and the shaft 8 is thereby turned. When the impression is thrown "off" it is necessary that the motion of the grippers be arrested also, and this is done by raising the claw 47 out of the notch 85 in the disk 45 whereby the shaft 46 is disconnected from the wheel 48 and the shaft is held at rest and always brought to rest in the same position by a lever 76 Fig. 2 which is pulled into a recess in a disk 77, 90 fixed upon the shaft 46 by means of a spring 78.

For actuating the claw 47 the machine is fitted with a bar 75 Fig. 4 which can slide in the standards and is provided with a truck 80 which is normally held in its inoperative position by a spring 81 and when so held acts upon the spring 74 to hold its wedge under the plate 73. Pivoted on the outside face of the standard 4 there is a lever 82 which is provided with a recessed end 84 and is actuated by a cam on a wheel 83 which is driven from the wheel 14. Pivoted on the bar 79 there is a lever 85 carrying a V-ended strip 86 which is designed to be 100 acted upon by the end 84 of the lever 82 but normally is held clear of the end 84 by suitably arranged springs. Above the end of the lever 85 there is a lever 87 which is connected by a spring to the hand impression 105 throw off lever 88 to allow of the lever 88 being operated at any time, and when the end 84 is clear of the piece 86 the connecting spring forces the piece 86 into the path of the end 84 and the rod 79 is moved endwise 110 at the next inward motion of the lever 82. This brings the truck 80 into the path of a lever 89 carried by the same axle as the claw 47 and the claw is then raised out of the notch in the disk 45. The spring 74 is also 115 liberated and draws its wedge from under the plate 73 and the impression rod strikes the stop 75 so that whenever the handle 88 is operated the impression is thrown off and the grippers brought to rest at the same 120 125 130

time. After the impression has been taken the printed sheet is carried by the grippers in the direction of the arrow 89 Fig. 6 and these grippers are opened as the truck 90 on the gripper lever 87 passes the cam 91 and the motion of the sheet is arrested by coming into contact with fixed fingers 92 while the grippers complete their motion. The sheet then falls on to a set of tapes 93 which are carried by rollers 94 and extend from the right hand side of the machine through the gripper ring 38 at the left hand side of the machine and any suitable distance beyond. The tapes 93 may have a slow continuous movement or be moved intermittently for each sheet delivered, or they may be moved any desired distance after any desired number of sheets have been delivered to them. In the arrangement shown the left hand end of the shaft 46 is fitted with a disk 95 carrying a cam 96 which gives motion to a ratchet lever 97. The ratchet timing wheel 98 actuated by the lever 97, is carried by a lever 99 and is fitted with one or more nose pieces 100 so arranged that when a nose piece is brought into contact with a fixed stud 101 the friction pulley 102 at the end of the lever 99 is brought into contact with the disk 95 and through the pulleys 103 and 104 and a driving cord, the tapes 93 are actuated to carry the printed sheet from under the grippers to the outside of the machine.

For opening the grippers to receive the sheet at the feeding position there is a lever 105 Fig. 6 which is fulcrumed on the inside face of the standard 3 and provided with a lug 106 which acts upon the truck 90 when the grippers are in the feeding position. For actuating the lever 105 the shaft 16 is provided with a cam 107 and the lever has a long axle which projects through a slot in the standard and carries a cam truck.

The feeding table which is described more fully hereafter is fitted to oscillate on axles 108 and is actuated by a cam 109 Fig. 3 on the shaft 16 through a lever 110, and axle 111 which has a bearing in the standard 4, a lever 113 inside the standard and a link 114 which is attached to the side frame 120 of the table. The surface of the table consists of a number of tapes which are continuously rotated from a pulley on the shaft 16 through the driving cord 114, 115 and 116 and suitable pulleys 117, 118 and 119 see Fig. 1.

The construction and arrangement of the mechanism for feeding the sheets to the grippers and for automatically stopping the motion of the grippers and throwing the impression "off" are shown more particularly in Figs. 7, 8, 9 and 10. The feeding table which is carried and actuated as hereinbefore described is built up of side frames 120 and 121 which are suitably connected together. At the upper end of the table

there is a tape roller 122 and at the lower end of the table there is an axle 123 provided with a separate roller 124 for each of the tapes 125. These tape rollers are inclined to the sides of the table so that the sheets fed at the upper end of the tapes are carried forward and toward the side lay 127. At the lower end of the table there is a set of fixed stop pins 128 and also a set of movable stop pins 129 which are fixed to a rod 130, and are normally held in their highest position by a spring. The pins 129 are also connected by a wire 132 to some fixed part of the machine so that as the table rises to its highest position the motion of the pins 129 is arrested. The side lay 127 is adjustably mounted on a frame 133 which is free to move without turning on a rod 134 carried by the side frames 120 and 121. Between the frame 120 and the end of the side lay frame 133 there is a spring 135 by which the side lay is pressed toward the frame 121 and at the other end of the frame 133 there is a wedge shaped collar 136 which is connected by a link 137 to a lever on the rod 130 and is fitted to work between inclined faces on the end of the frame 133 and on the side frame 121, by and through which the side lay receives a small motion toward the side frame 120 as the table completes its upward movement and the sheet is thereby positively moved to its side registering position. When the table is in its highest position a sheet is placed upon the tapes and carried by them up to the fingers 138. As the table is lowered these fingers are turned with their carrying axle through a lever 139 which comes into contact with a fixed stop 140. The tapes then carry the sheet up to the pins 129 and into contact with the side lay 127 by which time the table is partly raised and such sheet is smoothed and held in contact with the tapes by fingers 141 carried by a spindle 142 which may be fixed or free to turn in arms carried by the sides 120 and 121. The upward movement of the pins 129 is arrested relatively to the movement of the table when the upper end of the pins is just below or about level with the edge of the open gripper 36 and the side lay is also actuated as the table completes its upward movement through the turning of the shaft 130 and moves the sheet to its side registering position. Simultaneously with this action the tapes carry the sheet toward the pins 128 and between the grippers, which are then closed so that the movable gripper 36 follows the sheet as it is lifted by the rising table into contact with the fixed gripper 35 and the sheet is gripped just after it has been moved into contact with the fixed pin 128. The automatic throw out mechanism is brought into action through a feeler 143. This feeler is inside the path of the grippers as shown in Fig. 7 when the sheet is fed to

the grippers and when the grippers have closed this feeler is allowed to fall. If it rests on a sheet of paper then the lever 144 is held clear of the grooved end of a lever 145 and the motions of the machine are continued, but if no sheet is fed to the grippers then the feeler falls to the position shown in Fig. 9 and the lever 144 comes into position to engage the lever 145 and the rod 79 is moved endwise by the lever 82 Fig. 5. The feeler 143 is mounted on a light shaft 146 which is carried by bearings from the stretcher 2. At one end of the shaft there is the lever 144 and also another lever 147. Pivoted at 148 on the standard 4 there is a three armed lever the end *a* of which carries a cam truck which passes through the standard 4 and is operated by a cam 150 on the inner face of the wheel 83, Figs. 3 and 9 and 20 when so operated its end *b* acts upon the lever 147 to turn the shaft 146 and raise the feeler 143 to the position shown in Fig. 7. The third arm *c* of the three armed lever carries an axle for the lever 145 and if the upper end of this lever comes into contact with the lever 144 the lever 145 is turned on its axle as this axle moves around the center 148 and the lower arm of the lever 145 then depresses the lever 85, Figs. 4 and 9 whereby 30 the stop mechanism is automatically brought into action as previously explained. Connected to the lever 145 there is a spring 155 by which the lever is normally held in contact with a fixed stop 151 and which also 35 acts to hold the three armed lever in contact with its actuating cam.

The above machine is herein described with reference to the printing of sheets of paper, but it can also be used for cards, envelopes 40 and the like and by a suitable disposition of the friskets, grippers and stop pins, and tapes on the feeding table and the use of more than one side lay, two or more sheets, cards, envelopes or the like may be printed at 45 the same time, and the machine may be fed by hand or by any suitable arrangement of automatic selecting and feeding mechanism.

What I claim, in connection with platen printing presses is:—

50 1. The combination of a fixed platen, gripper bearing rings, gripper carrying rings mounted upon the said bearing rings, fixed grippers and movable grippers supported by the said carrying rings, a reciprocating rack for intermittently rotating the gripper carrying rings, and means for throwing the rack out of connection with the carrying rings when moved in one direction and into connection when moved in the opposite direction, substantially as set forth.

2. The combination of the gripper rings, grippers carried by such rings, a rack for intermittently rotating the gripper carrying rings, a bracket guiding the rack and fitted 65 to move vertically, cam mechanism for so

moving the rack bracket, and a slotted lever for moving the rack horizontally with a quick return motion substantially as herein described.

3. The combination of a fixed platen, gripper rings, grippers carried by such rings, means by which the gripper rings are intermittently rotated, locking lugs on one of the gripper rings, a locking fork working in conjunction with such lugs, a sliding bar 75 carrying the locking fork and cam mechanism actuating the said sliding bar and fork substantially as herein described.

4. The combination of a platen, gripper rings, the grippers carried by such rings, a fixed cam for opening the grippers, fixed fingers for removing the sheet from the grippers, a receiving table, a gear for driving the table, and timing mechanism for controlling the action of the gear substantially as herein described.

5. The combination of rotary grippers, a driving gear for actuating them, a driven disk, a crank pin carried by the said disk and through which the driving gear is actuated, a shaft on which the said gear is loosely supported and to which the crank-carrying disk is secured fast, a claw connection between the said driving gear and the disk, cam operated means adapted to throw out of engagement the said claw and thus stop the operation of the grippers, and impression throw-off devices arranged to bring into operation the said cam operated means, substantially as set forth.

100

6. The combination of the platen, the gripper mechanism, the oscillating type bed, the type bed shaft, an impression arm mounted thereon, an impression rod connected to such arm, a pivoted plate for the end of the rod 105 to slide upon, means for controlling the position of the plate, a spring carrying such means, mechanism for controlling the action of the spring, and a fixed stop for the impression rod to strike against substantially as herein described.

7. The combination of a fixed platen, gripper rings, grippers carried by such rings, mechanism for rotating the gripper rings, the frisket irons, a bar carrying such irons, 115 levers on which the bar can turn, cam mechanism operating the said levers and means for controlling the inclination of the frisket irons substantially as herein described.

8. In a printing press, the combination of 120 grippers for feeding the paper, mechanism for intermittently operating the grippers, means for throwing off the impression, a hand lever for operating the said throw-off means, a stop bar for automatically controlling the operation of the grippers and of the impression throw-off means, a lever pivoted to the said stop bar, a cam-actuated lever arranged to cooperate with the lever on the stop bar, another lever arranged to cooperate 125

130

ate with the lever on the stop bar, and a spring connection between the last said lever and the hand throw-off lever, substantially as herein described.

9. The combination of a platen, intermittently rotating gripper mechanism, a feeding table, a supporting shaft, a feeler mounted upon the said shaft, a three-arm lever, one of the arms of which carries an axle, a lever on the shaft carrying the feeler and co-acting with one of the arms of the three-arm lever, a two-arm lever fulcrumed on the axle carried by another arm of the three-arm lever, and a cam mechanism actuating the three-arm lever, substantially as set forth.

10. The combination of a fixed platen, gripper rings, grippers carried by the rings and arranged in pairs, one of each pair being stationary and the other movable, mechanism for rotating the gripper rings and for opening and closing the grippers, a movable feeding table arranged to deliver to the grippers, means for stopping the sheets upon the feeding table, and mechanism for mov-

ing the feeding table toward the grippers, such mechanism and the gripper closing mechanism being timed so the movable gripper follows the sheet as it is carried by the feeding table toward the stationary gripper, substantially as set forth.

11. The combination of a fixed platen, gripper rings, grippers carried by the rings, mechanism for operating the gripper rings and for opening and closing the grippers, a feeding table, means for moving the sheets to and across the feeding table, a set of stops for arresting the sheets before they are moved into position to be engaged by the grippers, means for moving the feeding table toward the grippers and in so doing carrying the sheets out of engagement with the aforesaid stops, and a second set of stops in advance of those first mentioned for arresting the sheet in position to be engaged by the grippers, substantially as set forth.

CHARLES BUTTERFIELD.
